[57] **ABSTRACT**

Means for improving separation between a transducer operating surface and a moving record media. Nonuniform pressure distribution between the media and the operating surface produces a cocking tendency in the media increasing upstream separation and decreasing downstream separation over the processing zone in the transducer. This invention recognizes that the cocking tendency is caused by a region of lower than ambient pressure near the point where the media draws away from the operating surface, and provides means for supplying ambient pressure at that point. In a preferred embodiment, the means comprises a transverse slot extending beyond the side edges of the media.

**SEPARATION CONTROL FOR RECORD MEDIA
TRANSDUCER WITH TRANSVERSE SLOTS TO SUPPLY
AMBIENT PRESSURE**

BACKGROUND OF THE INVENTION

The present invention relates to magnetic transducer apparatus, and more particularly to flexible web record media transducers of the type which employ fluid bearings between the operating surface of the transducer and the moving media to reduce wear and control separation.

The use of fluid bearings between moving magnetic record media, such as magnetic tape, and a transducer employed to write on or read from the media, has become popular in recent years. Techniques for generating such bearings and controlling their thickness are taught in U.S. Pat. No. 3,170,045 and U.S. Pat. No. 3,416,148, both assigned to the assignee hereof. The techniques described involve passing the media over a curved operating surface to develop a bearing whose thickness is a function of various parameters, including the curvature of the surface, record media velocity, the angle of wrap and tension on the media, and the viscosity of the fluid from which the bearing is created. The patents further point out that the stability of the bearing and the uniformity of its thickness are, in part, a function of the arc length over which it exists along the operating surface of the head. The present invention is concerned with situations wherein it is desirable to provide a uniform fluid bearing over a length of operating surface, but where the wrap angle and operating surface contour are such, with respect to the media involved, that a constant and uniform bearing cannot be guaranteed. Such a situation exists, for example, where the operating surface includes a pair of generally flat surface portions that are inclined only a few degrees relative to one another and are joined by a small radius portion. The record media assumes an angle of wrap over the radius portion and a bearing is generated, but, due to the short arc length involved, precise control and stability are difficult to achieve. It is found that the bearing developed in this case often varies in thickness along the radius portion. It is also found that the point of closest proximity between the radius portion and the media shifts, depending upon the direction the media is travelling. If a transducing gap is located in the radius section, these variations can cause variations in the signals recorded on or read from the media by the gap. Unless the gap is located precisely midway between the points of closest proximity for each direction of media travel, a different separation is found at the gap for each direction of motion and different transducing action takes place. A magnetic tape read in the "forward" direction of tape motion in this situation will produce different signal strengths than when read in a "backward" direction.

It is important in a present day magnetic tape processor that the "forward-backward" ratio of transduced signal characteristics be maintained as nearly equal to 1:1 as possible for error-free operation. Accordingly, it is the principal object of this invention to provide, in a transducer having transducing gaps located in radius portions of its operating surface, means for stabilizing the fluid bearing between the moving record media and the radius surface, and for ensuring uniformity of its thickness. It is a particular object of the invention to improve the uniformity of the bearing thickness for both directions of motion of the media.

SUMMARY OF THE INVENTION

An important aspect of this invention is the discovery that a flexible record media of a given stiffness, such as a conventional magnetic tape, passing over a radius on an operating surface, generates fluid bearing pressure, the distribution of which is not symmetrical between the entry and exit points of tangency between the media path and the surface. In actuality, the moving media does not leave the surface at the exit point of tangency determined by its wrap angle, but tends to follow the surface further than it should. Analysis of the pressure distribution between the media and the surface has shown that

this situation results from the presence of a negative pressure region near the exit point of tangency. This negative pressure region seems to be produced by the increase in the volume of the space between the media and the surface as the media leaves the surface, and an inability of the environmental fluid to fill the space adequately under the conditions present. The media is, accordingly, drawn toward the surface and "cocked" downstream. In cases where the wrap angle is small and the length of the fluid bearing is short, the cocking contributes to nonuniformity of separation over the distance between the entry and exit tangency points. It produces a varying separation that has a position of closest proximity nearer the exit tangent point than the entry tangent point. This closest proximity position, thus, differs for each direction of motion of the media and produces an undesirable forward-backward signal ratio, as earlier described, unless the transducing gap on the radius surface is positioned exactly midway between the two tangency points. Such fine positioning is difficult, if not impossible, to obtain.

According to this invention, the cocking problem is solved by providing a slot in the operating surface of the transducer at the position where the negative pressure region is found to have existed. The slot extends transversely of the direction of motion of the media and communicates with the ambient fluid environment at the sides of the media. Its width and depth dimensions are sufficient to produce ambient pressure between the media and the surface at the exit tangency point, thus dissipating the negative pressure region and allowing the media to depart along the path dictated by the wrap angle. It has been found that, by provision of this slot, the tendency to cock is eliminated and the fluid bearing over the length of operating surface between the entry and exit tangency points is greatly enhanced in terms of stability and uniformity of thickness. Criticality of location of the transducing gap is thus eliminated. By providing a slot at each side of the transducing gap, located to prevent cocking for both directions of travel of the media, uniformity of separation in both forward and backward operation modes is achieved and a forward-backward ratio of substantially 1:1 is achieved.

The foregoing and other objects, features, and advantages of the invention will be apparent from the following more particular description of preferred embodiments of the invention, as illustrated in the accompanying drawings.

BRIEF DESCRIPTION OF THE DRAWINGS

In the drawings:

FIG. 1 is a schematic representation of a transducer having a transducing gap positioned in a radius portion of its operating surface, and illustrating the cocking tendency of a record tape passed therover at a small wrap angle;

FIG. 2 is a plot of the fluid bearing pressure distribution between the transducer operating surface and the record tape of FIG. 1;

FIG. 3 is a plot of the separation between the tape and operating surface of FIG. 1;

FIG. 4 is a schematic representation of a transducer similar to that of FIG. 1, but having slots provided in accordance with this invention;

FIG. 5 is a plot of the fluid bearing pressure distribution between the transducer operating surface and the record tape of FIG. 4;

FIG. 6 is a plot of the separation between the tape and operating surface of FIG. 4; and

FIG. 7 is a schematic representation of a transducer having plural transducing gaps spaced along the direction of tape motion showing the provision of slots for each gap-containing area of the operating surface.

DETAILED DESCRIPTION

Referring now in detail to the drawings, FIG. 1 shows an enlarged elevational view of the contour of a portion of a transducer 10 having an operating surface 12 over which a mag-

magnetic record tape is passed. The surface 12 has a width dimension (into the plane of the paper) at least equal to and preferably greater than the width of the record tape and is generally smooth and continuous over the length shown. As illustrated in FIG. 1, the surface includes a radius portion 14 that blends at each end with two generally flat portions 16 and 18 that are inclined one to the other. The radius portion 14 comprises a processing zone of the transducer structure and a transducing gap 20 is positioned within it. The magnetic head element that forms the gap is partially shown in dotted outline at 22.

A magnetic record tape to be processed is passed over the operating surface along the path indicated by the solid line 24. As may be seen, the path of the tape is such that a small wrap angle over the radius portion 14 is achieved. The wrap angle is provided by means (not shown) that cause the tape to enter and leave the processing zone of the transducer at the angle shown. The means may include tape guides or fluid pressure means that constrain the tape. Its specific configuration is not a part of this invention and will not be described herein.

In accordance with the principles described in the patents mentioned earlier herein, passage of the tape along path 24 over the operating surface 12 produces a fluid foil bearing between the tape and the surface 12 from the environmental fluid in which the apparatus resides (for example, air). The bearing produces a separation between the tape and the surface 12 that lubricates the system and prevents excessive wear on both elements. The thickness of the bearing has been greatly exaggerated in the drawings for the purposes of illustration; it is, in reality, usually in the order of 30-100 microinches, depending upon the several parameters which control its generation.

The fluid bearing generated in the arrangement shown exists substantially over the arc length between the points where the tape path 24 becomes tangent to the radius portion 14 of the surface 12. These points are identified in FIG. 1 at the intersections 26 and 28 of radius lines R with the path 24. Depending upon the direction of travel of the tape, one of the points 26 or 28 is an entry point of tangency and the other is an exit point of tangency. These points of tangency are located with respect to the static or desired tape path determined by its wrap angle. It will be appreciated from the following description that the tape does not always follow the preferred path, however, and tends to enter and leave the processing zone at points which vary from the point of tangency. It is desirable that the bearing between the points of tangency be stable and uniform in thickness so that the tape follows essentially the preferred path 24 and good uniform transducing action can be achieved between the tape and the gap 20. It has been found, however, that in arrangements such as is shown, where conventional tape is used and where the wrap angle is small (for example, in the order of about 10° or less) and the radius of curvature of the portion 12 is also small (for example, less than one inch), there is not a sufficient arc length between points 26 and 28 to ensure a good stable and uniform bearing over the processing zone. It has been discovered that, for a given direction of travel, the tape actually cocks downstream somewhat, assuming paths shown at 30 and 32 in FIG. 1. Path 30 is assumed for a left to right direction (arbitrarily called "forward," hereinafter) of travel, while path 32 is assumed for the reverse ("backward") direction.

This cocking has been discovered to result from a nonsymmetrical pressure distribution between the tape and the operating surface. That pressure distribution is shown in FIG. 2. The horizontal axis of the plot of FIG. 2 corresponds in scale to FIG. 1. Two curves 34 and 36 are shown. Curve 34 shows the pressure distribution for forward travel, and curve 36 shows the distribution for backward travel. It will be seen that, for each direction, there exists a positive pressure region over a substantial length of the operating surface between the points of tangency 26 and 28, and then a negative pressure region (indicated by a dip of the curve below the horizontal axis) at about the exit point of tangency where the tape should

pull away from the surface 12. This negative pressure region seems to be produced by an inability of the ambient fluid to adequately flow into the increasing space beneath the tape under the conditions present when the tape is moving at high speed. The net result is that the negative pressure region draws the tape down at the exit point and moves the point of tangency downstream. The effect also tends to move the entry point of tangency downstream and results in the cocked condition shown by lines 30 and 32. The extent of the cocking effect, and the exact position of the negative pressure region are a function, in part, of the tape stiffness and may vary somewhat for different tapes.

The amount of cocking in each case is exaggerated in FIG. 1 for illustration purposes. It is more accurately shown by the tape-to-operating surface separation plot of FIG. 3. In this plot, the curves 38 and 40 illustrate the variation in separation of the tape for forward (curve 38) and backward (curve 40) travel with respect to the surface of portion 14. The horizontal scale of FIG. 3 corresponds to that of FIGS. 1 and 2 to permit ready comparison. Examination of FIG. 3 shows that, for each direction of travel, the separation distance varies widely between the entry and exit points of tangency, and includes a point of closest proximity that is not positioned midway between the tangency points, but is moved downstream toward the negative pressure region. It will be apparent from inspection of the curves 38 and 40 that, unless the transducing gap 20 is precisely positioned at the exact center of the length of operating surface between the points 26 and 28, different separation will exist at the transducer for each direction of tape motion and an undesirable forward-backward signal ratio is found. In FIG. 1, the position of the gap 20 is shown as being offcenter slightly. The separation distances at the gap position for each direction of motion are shown by the intersections of curves 38 and 40 with the line 42 in FIG. 3.

Exact positioning is, of course, not possible within ordinary manufacturing techniques. Additionally, some variation of the separation curves 38 and 40 occurs during operation of the apparatus due to various changes in tape stiffness, wear, etc., so separation differences for different tape motion directions will still exist.

The problems discussed in connection with FIGS. 1 through 3 are solved in accordance with this invention by the provision of means to eliminate the substantial negative pressure region 45 between the tape and the operating surface, and thereby eliminates the cocking tendency of the tape as it travels over the processing zone. The means comprises a slot in the operating surface extending transversely of the directions of motion of tape travel. FIG. 4 shows a transducer 10' like that of FIG. 1 having slots 44 and 46 provided therein for this purpose. Each slot 44 or 46 extends across the operating surface 12' of the transducer 10' a distance at least greater than the width of the tape and, preferably, from one side edge of the transducer to the other. FIG. 7 shows, in perspective, the arrangements of such slots at 116, in a complete transducer assembly.

The purpose of the slots 44 and 46 is to provide means to produce ambient fluid pressure at the points where the deleterious negative pressure is found to exist. Accordingly, they must be of sufficient depth and width to carry the volume of fluid required for this purpose and they must communicate with the ambient fluid at the sides of the tape. While two slots are shown in FIG. 4, it will be appreciated that, for a given direction of motion, the downstream slot is of primary interest. Thus, for forward motion, slot 46 provides the anticocking control, while slot 44 controls the effect for backward motion. The positioning of the slots is important. For each direction of motion, the slot must be within the area of the operating surface portion at which the negative pressure is found to have existed. Generally speaking, this is near the exit point of tangency. From the plot of FIG. 2, it will be seen that the negative pressure region extends upstream from the exit tangency point 28' (forward) or 26' (backward) somewhat, so it is useful to locate the upstream edge 44A or 46A of the slot somewhat inside that point. Some variation in

positioning may be permitted so long as the slot's upstream edge 44A or 46A is within the negative pressure area and capable of equalizing the pressure enough to prevent cocking. Experimentation on a given operating surface contour to establish the negative pressure point will establish the proper position for that contour.

As previously mentioned, the presence of two slots 44 and 46 provides for elimination of the cocking problem in each direction of tape motion. The upstream slot is not essential for a given direction and, in a transducer arranged only for unidirectional tape motion operation, it may be eliminated. It has been found, however, that such a slot is beneficial in that it tends to bleed off some of the fluid that is dragged beneath the tape to form the fluid bearing and aids in producing thin bearings that improve transducing action. As described in the patents mentioned earlier herein, the bearing thickness is directly proportional to the radius of curvature of the operating surface in the area where the bearing is generated. Accordingly, by bleeding off some of the fluid via the upstream slot to reduce the thickness, larger radii of curvature can be provided without production of excessively thick bearings, and the pressure loading on the tape and operating surface can thereby be minimized. This last relationship can be understood by considering that the pressure is proportional to the tape tension per unit width, divided by the radius of curvature.

FIG. 5 shows the pressure distribution between the tape and operating surface in the embodiment of FIG. 4. It will be noted that the negative pressure region has been effectively eliminated by the slot 46 for forward motion (curve 34') and by the slot 44 for backward motion (curve 36'). Reference to FIG. 6 shows that the separation of the tape from the operating surface is substantially constant along the processing zone, providing an equal separation for each direction of motion at the transducing gap 20'. The tape, then, is found to travel substantially along the path 24' of FIG. 4 without any objectionable cocking tendency in either direction. The necessity for precise gap location is eliminated and any location within the land area 48 of the surface 14' between slots 44 and 46 is acceptable.

The slots 44 and 46 are a preferred means for supplying ambient fluid pressure beneath the tape at the negative pressure regions. It should be understood, however, that other equivalent means, such as holes in the operating surface at the points where the slots 44 and 46 are shown, would suffice. Such holes would, of course, communicate with a source of ambient pressure.

Although actual dimensions of the various elements are not considered to be necessary for an understanding of the invention, and will vary widely depending upon the transducing requirements of a given record media-processing system, there are given below the general parameters of the embodiment shown in FIG. 4. This transducer is intended to operate with a conventional half-inch magnetic record tape travelling at 200 inches per second, with air as the fluid environment.

$R = 0.5$ inch.

Land Area 48 = 0.04 inch between slots 44 and 46.

Angle of Wrap = 7°.

Slots 44 and 46 = 0.006 inch deep and 0.04 inch wide (from upstream wall to downstream wall).

Average tape-to-surface separation at gap 20' = 30 microinches.

FIG. 7 of the drawings is a perspective illustration of a multitrack transducer 100 provided in accordance with the principles of this invention. As may be seen, the transducer 100 has two transducing gaps 102 and 104 in each information channel or track along its operating surface 106. The purpose of the two gaps in each track is to permit simultaneous writing and reading operations, as is well understood in the art. The operating surface 106 is arranged to have a flat central portion 108 with flat leading and trailing portions 110 and 112 extend-

ing outwardly in each direction at an angle thereto. The portions 110 and 112 are joined to the central portion by small curved portions 114 of radius r within which the transducing gaps are located. The portions 114 correspond to the radius portions 14' of FIG. 4. Near the points where each radius portion 114 joins each of its adjacent flat portions, a slot 116 is provided. The slots 116 provide the functions described with respect to slots 44 and 46 of FIG. 4, and they are located near the points of tangency of the tape path with the radius portions 114 to relieve the negative pressures earlier described. In this transducer 100, the tape actually experiences the situation described with reference to FIG. 1 twice during its travel over the operating surface 106; once as it is wrapped over each radius portion 114 between the center flat surface 108 and one of the end flat portions 110 and 112.

Near the opposite ends of the portions 110 and 112, additional slots 118 are seen in FIG. 7. These slots are coupled to a source of vacuum pressure and operate to load the tape (not shown) downwardly over the transducer 100 to create the wrap angle necessary for generation of fluid bearings at the radius portions 114 and control of the tape separation at the transducing gaps. Longitudinal slots 120 extend toward the radius portions from the vacuum slots 118. These slots 120 are positioned to underlie the side edges of the tape as it passes over the transducer and exert a downward force to prevent any tendency of the edges to curl upwardly.

Additional longitudinal intertrack slots 122 may be provided in a transducer 100 to provide a channelling action for a portion of the fluid bearings over the surfaces 114 to further reduce their thicknesses. The function of the slots 122 in no way adversely affects the anticocking action of slots 116.

While the invention has been particularly shown and described with reference to preferred embodiments thereof, it will be understood by those skilled in the art that various changes in form and details may be made therein without departing from the spirit and scope of the invention.

What is claimed is:

1. In a magnetic tape transducer of the fluid bearing type which has an operating surface including a radius portion connecting inclined flat surface portions over which a length of magnetic tape, significant lengths of which appear rigid, having a fixed width is adapted to be moved in either of two directions, said tape being arranged to have an angle of wrap about the radius portion of the operating surface that produces spaced entry and exit points of tangency with said surface for each direction of movement, and wherein movement of the tape over said operating surface generates a fluid bearing between said tangency points, the improvement in means for providing a uniform bearing over a substantial portion of said operating surface between said points of tangency for each direction of tape motion, comprising a slot, extending transversely of the direction of tape motion, immediately adjacent said exit point of tangency, within a distance from said exit point corresponding to a short length of apparently rigid tape, and substantially longer than the tape width for supplying ambient fluid pressure between the tape and the operating surface when the tape is moving in a direction toward said exit point of tangency from the entry point of tangency
2. The invention defined in claim 1, wherein the transverse slot has a cross-sectional area sufficient to produce ambient fluid pressure throughout its volume.
3. The invention defined in claim 2, wherein there are two of said slots extending transversely of the direction of tape motion and positioned between the spaced-apart entry and exit points of tangency.
4. The invention defined in claim 3, wherein the magnetic tape is a conventional one-half-inch-wide record tape of average stiffness, wherein the radius portion of the operating surface has a radius of less than one inch, and wherein the angle of wrap is less than 10°.
